(57) CLAIM

The ornamental design for a wall brace, as shown and described.

DESCRIPTION

FIG. 1 is a perspective view of a wall brace showing my new design;

FIG. 2 is a detail view in perspective of one end thereof;

FIG. 3 is a side elevation view thereof;

FIG. 4 is a top plan view thereof;

FIG. 5 is a bottom plan view thereof;

FIG. 6 is a perspective view of a wall brace showing a second embodiment of my new design;

FIG. 7 is a detail view in perspective of one end of the wall brace shown in FIG. 6;

FIG. 8 is a side elevation view thereof;

FIG. 9 is a top plan view thereof; and,

FIG. 10 is a bottom plan view thereof.

FIGS. 2 and 7 are shown in a fragmented and enlarged manner for clarity of illustration.
